CLAIM

The ornamental design for a pickleball paddle as shown and described.

DESCRIPTION

FIG. 1 is a perspective view of the pickleball paddle of my new design from the front, top;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof taken along line 8-8 of FIG. 2; and,

FIG. 9 is a cross-sectional view thereof taken along line 9-9 of FIG. 2.

The portions of the drawings shown in broken lines form no part of the claimed design.
